LOOM LETOFF

Dewey L. Moore and Ben O. Morrow, Chester,
S. C.

Application April 12, 1939, Serial No. 267,496

1 Claim. (Cl. 139—113)

This invention appertains to new and useful improvements in looms and more particularly to the usual letoff pinion shaft and external gear such as is well illustrated in the patent to C. F. Roper, No. 843,181, filed March 15, 1906, for Letoff mechanism for looms.

The principal object of the present invention is to provide an improvement of the character stated which in use will reduce the amount of inferior cloth, known as "seconds" and which usually consists of cloth with thin areas or wavy areas.

Another important object of the invention is to provide an improved letoff mechanism for looms wherein the usual external gear is maintained in operation in a smooth and even manner and also to the extent that while this manner of operation reduces the amount of inferior cloth it also reduces wear on the letoff pinion shaft and external gear.

Other objects and advantages of the invention will become apparent to the reader of the following specification:

In the drawings:

Figure 1 represents an end elevational view.
Figure 2 is a fragmentary side elevation.

Figure 3 is a fragmentary cross sectional view longitudinally of the apparatus.

Figure 4 is a front elevational view of the improved letoff pinion shaft arm unit.

Figure 5 is an end elevational view of the arm shown in Figure 4.

Figure 6 is an inside elevational view fragmentarily showing the letoff pinion shaft arm unit.

Referring to the drawings wherein like numerals designate like parts, it can be seen that numeral 5 represents the pinion shaft which carries the pinion (not shown) and on which is also located the ratchet wheel 6 and gear 7, both being conventional features of a loom letoff.

Numeral 8 denotes the usual letoff outside bearing carried by the shaft 9.

In carrying out the present invention, the pinion shaft handle hub 10 has two pair of ears, namely the pair of ears 11 and the pair of ears 12, the latter being disposed from the hub at a position diametrically opposite from the ears 11.

A pinion shaft handle 13 is swingably mounted as at 14 between each pair of ears 11—12 as is clearly shown in Figure 3.

In further carrying out the present invention, the improved pinion shaft arm unit generally referred to by numeral 15 consists of the internal hub 16 across the inner end of which extends the channeled carrier 17 for the pawls 18 and 19.

These pawls 18—19 are beveled at their inter-

nal gear engaging ends as at 26 and are in the form of arms 21 rockably supported as at 22 and having their inner reduced ends 23 in the path of the slide pin 24. These slide pins have their outer ends in the path of the lugs 25 on the inner ends of the pinion shaft handle 13.

Springs 26 are interposed between the channeled cross member 17 and the pawl arms 21—21 for normally urging the beveled pawls 18 and 19 into engagement with the ratchet 10 wheel 6.

In the patent to Roper No. 843,181 the pinion shaft Bx corresponds to the pinion shaft 5 clearly shown in Figure 3 and the handle 26 in that patent corresponds to the handle 13 which is clearly shown in Figures 1 and 2 of the present drawings. The operation of the letoff pinion shaft arm as now used on present day looms and which is only single in number as in the Roper patent is often irregular in operation and produces wear that can be overcome by the employment of these handles in diametrically opposite positions as illustrated in Figures 1 and 2. The letoff pinion shaft arm now employed on most looms has only one pawl to contact the teeth on the ratchet wheel 6, whereas the present invention employs two pawls with the marked tendency to eliminate the one sided wear that is caused by the singly provided type. Through the pins 16 a more even operation of the pawls 21 is obtainable.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

In a loom, a letoff mechanism including a letoff pinion shaft, a ratchet wheel on the pinion shaft, a letoff pinion shaft arm assembly, a pinion shaft handle assembly, said pinion shaft arm assembly including a pair of pawls mounted on the shaft and for engagement with the ratchet wheel, and drive means between the pinion shaft handle assembly and the pawls whereby the pawls are operated simultaneously in response to action of the handle assembly, said handle assembly including a pair of swingable weighted handle members and pin members movable in response to the action of the said handle members to effect operation of the pawls, said pawls being disposed at diametrically opposite sides of the said shaft.
